UNITED STATES PATENT OFFICE.

JOHAN HENRIC SALOMON JOHNSON, OF MALMO, SWEDEN, ASSIGNOR TO AKTIEBOLAGET CELTIC, OF MALMO, SWEDEN.

PACKING-CASE.

No. 873,866.

Specification of Letters Patent.

Patented Dec. 17, 1907.

Application filed August 10, 1906. Serial No. 330,063.

To all whom it may concern:

Be it known that I, JOHAN HENRIC SALOMON JOHNSON, a subject of the King of Sweden, residing at Fredsgatan 24, Malmo, Sweden, have invented certain new and useful Improvements in Packing-Cases; and I do hereby declare the following to be a full, clear, and exact description of the invention, such as will enable others skilled in the art 5 to which it appertains to make and use the same, reference being had to the accompanying drawings, and to letters or figures of reference marked thereon, which form a part of this specification.

15 This invention relates to improvements in collapsible packing cases or boxes and the objects of the invention are first, to provide improved means for easily and quickly uniting the parts for use and to disunite them for 20 the purpose of packing them into a small bundle for shipment; second to provide means for an effective and easy locking of the assembled parts.

In the accompanying drawings, Figure 1 25 is a transverse vertical section of my improved box or case. Fig. 2, a horizontal section on the line A B, Fig. 1. Fig. 3, a longitudinal vertical section on the line C—D, Fig. 1. Fig. 4 is a top view of the box, and 30 Fig. 5, an enlarged detail view of the locking device.

The box or case comprises as usual a top *a*, bottom *b*, two opposing sides *c*, *c* and two sides or ends *d*, *d*.

35 The top and bottom edges of the sides *c*, *c*, are flush with the outer faces of the top and bottom and the ends of the sides flush with the ends of the top and bottom. The sides or ends *d*, *d* fit between the sides *c*, *c*, and between the top and bottom, the top and bottom having their inner faces cut away a distance equal to the thickness of the ends forming a flange against which the ends abut and preventing any inward movement thereof.

40 The sides and ends are held against outward movement from the top and bottom by means of angle-strips *e* secured to the outer faces of said top and bottom. The strips that hold the sides *c*, *c* project over the top 45 and bottom edges thereof while the strips that hold the sides or ends *d*, *d* lie against the edges of said top and bottom and project over the outer faces of the ends.

By the above described construction it is 50 only necessary to fasten the sides to the top

and bottom whereupon the ends are prevented from being displaced. This I accomplish by means of bolts *f*. While I have shown only four of these bolts which are arranged in pairs in line with each other, it will 60 be apparent that any number may be used according to the length of box desired. The bolts lie in grooves *g* formed in the top and bottom and are retained in said grooves preferably by such means as plates *h*. The bolts 65 of each pair are thrown in opposite directions, their outer ends taking into perforations or holes formed in the sides *c*, *c* which holes are closed on the outside by the strips *e*. The inner ends *i* of the bolts are bent at 70 right-angles as shown in Fig. 2. This angular portion serves both as a handle for manipulating the bolts, and as a locking means, the slots in the bottom being provided with an off-set to receive the end *i* after the bolt 75 has been thrown into locking position.

In order that the bolts in the top may be manipulated after the top has been placed in position I provide openings *k* into which the end *i* project as shown in Fig. 4. These 80 openings may be sealed by any well known means.

When the case is to be taken apart, the bolts of the top are withdrawn from the holes in the sides and the top and ends thus liberated. After the contents of the case has 85 been removed the bolts in the bottom are rotated, for the purpose of removing the ends *i* from the off-set, when they may likewise be drawn from the holes. The sides are now 90 liberated from the bottom and all the parts may be put into a compact bundle.

When the case is to be assembled, the sides *c* are first placed inside the angle-strips *e* on the bottom, the bolts thrown and the ends *i* turned down into the off-set. If the nature of the goods permits they may be packed between the sides whereupon the ends *d* are inserted between the ends and the cover *a* placed on the upper edges of the sides and 95 ends. The bolts of the cover are pushed into the holes on the sides *c* and the case is locked. The sides and ends may be placed simultaneously on the bottom if desired.

I claim:—

A box comprising a top and a bottom, two side pieces whose edges are flush with the ends and outer faces of the top and bottom, angle-strips secured to the top and bottom projecting beyond their edges and over the 110

105

edges of the side-pieces forming grooves to receive the latter, end-pieces mounted between the side-pieces in recesses formed in said top and bottom, the outer faces of the 5 ends flush with the edges of the top and bottom, angle-strips on the top and bottom engaging the last named edges and outer faces of the ends, bolts slidably mounted in grooves formed in the top and bottom and adapted 10 to take into apertures formed in the sides, a head on each bottom bolt adapted to be

turned into an offset which communicates with the bottom slots, and apertures in the top to permit access to the bolts therein.

In testimony, that I claim the foregoing as 15 my invention, and have signed my name in presence of two subscribing witnesses.

JOHAN HENRIC SALOMON JOHNSON.
